[57] CLAIM

The ornamental design for an automatic wire cutting machine, as shown and described.

DESCRIPTION

FIG. 1 is a perspective view, taken from the top, front, right side, of an automatic wire cutting machine showing our new design;

FIG. 2 is a reduced front elevational view thereof;

FIG. 3 is a reduced rear elevational view thereof;

FIG. 4 is a reduced right side elevational view thereof;

FIG. 5 is a reduced left side elevational view thereof;

FIG. 6 is a reduced top plan view thereof, the bottom being unornamented.

FIG. 1

FIG. 2

FIG. 3

FIG. 4

FIG. 5

FIG. 6
